UNITED STATES PATENT OFFICE

FRED P. DISTER, OF HAMILTON, OHIO, ASSIGNOR TO AMERICAN CAN COMPANY, OF NEW YORK, N. Y., A CORPORATION OF NEW JERSEY

APPARATUS FOR PREPARING DRUM HEAD CAN BODIES

Application filed February 13, 1929. Serial No. 339,503.

This invention relates to an apparatus for providing a cylindrical can body with a supporting shoulder, assembling a drum head within the can body and against the shoulder and curling the edge of the can body to hold the drum head in position.

The usual type of drum head can adapted to be produced by the apparatus of the present invention comprises a metallic cylindrical can body having a bottom or end member and a frangible drum head forming a seal for the top of the can. A supplemental cover of the friction or the slip cover type is usually used in connection with the sealed drum head and forms a protection for the drum head prior to its being cut out in the first opening of the can after which this supplemental cover provides a reclosure. The apparatus of the present invention relates to forming the drum head seal in one end of the can body and flanging its opposite end for the reception of the bottom or end member.

The principal object of the present invention is the provision of an apparatus for first preparing an annular can body for the reception of a drum head, and second, positioning and securing the drum head within one end of the body.

Another important object of the invention is the provision of a drum head inserting mechanism which receives a drum head in proper alignment with a can body and which holds the same in aligned position during its insertion.

Still another important object of the invention is the provision of an apparatus that simultaneously operates on both ends of a can body, forming one end for the reception of a drum head, and flanging the other end for the reception of a can bottom.

Another important object of the invention is the provision of an apparatus for moving successive can bodies in one general direction or line of travel and performing various operations on each succeeding can body as it is conveyed through the machine.

Numerous other objects and advantages of the invention will be apparent as it is better understood from the following description, which, taken in connection with the accom-

panying drawings, discloses a preferred embodiment thereof.

Referring to the drawings:

Figure 1 is a rear elevation of the apparatus, parts being omitted; 55

Fig. 2 is an end elevation of the apparatus, the view being taken of the end of the machine containing the mechanism for operating upon the top section of the can body;

Fig. 3 is a front elevation of the apparatus; 60

Fig. 4 is an end elevation, the view being taken of the end of the machine containing the mechanism for operating upon the bottom section of the can body; 65

Fig. 5 is a longitudinal central sectional view of the apparatus, being taken substantially along line 5—5 of Fig. 2;

Fig. 6 is a transverse section taken substantially along line 6—6 of Fig. 1; 70

Fig. 7 is a transverse section, taken substantially along line 7—7 of Fig. 1, parts being broken away;

Fig. 9 is a transverse fragmentary section, taken along line 9—9 of Fig. 1;

Fig. 10 is a transverse fragmentary section, taken substantially along line 10—10 of Fig. 1; 80

Fig. 11 is an enlarged longitudinal sectional view of the supporting shoulder forming and can body flanging mechanisms, parts being broken away;

Fig. 12 is an enlarged longitudinal sectional view of the drum head inserting and securing mechanism, parts being shown in elevation and parts being broken away; 85

Fig. 13 is a view similar to Fig. 12 showing the drum head inserting and securing mechanism in a different position relative to the can body, and 90

Fig. 14 is an enlarged detail in elevation of the drum head inserting and securing mechanism, the view being taken at right angles to Fig. 13. 95

In the machine disclosed in the drawings, annular non-flanged can bodies are received from an inclined type of runway or chute into the pockets of an intermittently mov- 100

ing turret, this turret constituting a can body carried. The turret conveys each can body, in a step by step movement, through an idle station and brings it to rest at the first operating station. While in this station, both ends of the can body are simultaneously engaged by operating mechanism.

A supporting shoulder is formed on the top end of the can body by a mechanism comprising a beading head carrying an outside beading roller or hollow cup member which moves over the top end of the body, and an inside beading roller which moves into the top end of the can body. Both rollers rotate during the shoulder forming operation, the axes of the rollers at such a time moving eccentrically to each other, clamping the can body wall at a point of tangency between peripheral beading surfaces formed on the rollers.

Simultaneously a flange is formed on the bottom end of the can body by mechanism operation in a similar manner, this comprising a flanging head carrying an outside flanging roller or hollow cup member which moves over the bottom end of the can body and an inside flanging roller which moves into the bottom end of the can body. Both of these rollers rotate during the flanging operation, the axes of the rollers at such time moving eccentrically to each other and clamping the can body wall at a point of tangency between peripheral flanging surfaces formed on the rollers.

Beading and flanging heads are then separated releasing the can body which is thereupon moved by the turret to the next station. At this station, a drum head is inserted within the shouldered top end of the can body and is secured therein.

A frangible drum head, which may be a flat disc as illustrated in the drawings, is brought into the machine on a horizontal chain conveyer and is projected into a vertical chute carried by an inserting and securing head located at the second station. The disc is retained in the chute until the head is in proper position to receive it at which time it is released, and falling into a pocket comes to rest within holding fingers carried by the head. The disc is thereby held in a vertical position and in axial alignment with the can body.

The inserting and securing head, which is carried on a sliding, non-rotating shaft, then moves over the top end of the positioned can body, and a rotating backing head carried on a sliding rotating shaft moves into engagement with the bottom end of the body. The can body is thereby clamped between the two heads and the disc is forced into the top end of the body. The can body rotates with the rotating backing head, and the upper edge thereof engaging curling rollers carried by the inserting and securing head

is bent over into an annular curl which presses against the drum head, securing it between the curl and the shoulder of the can body. The two heads thereupon separate, freeing the can body and permitting it to be moved with the next movement of the turret, which movement discharges it from the machine.

The various parts of the apparatus are carried by a bed 21 mounted upon supporting legs 22 (see Figs. 1 to 6 inclusive). Most of the shafts and other operating parts of the machine are supported above the bed, there being provided for this purpose an end bracket 23, a central supporting frame 24 and an end supporting frame 25, all carried upon the bed 21.

Annular can bodies "A", which may be cylindrical as illustrated in the drawings, are conveyed to the machine by a usual type of chute 26 which may consist of spaced angle irons. The lowermost pair of angle irons or rails 27 are curved at their bottom extremities to form a passageway for the can bodies as they are conveyed to the first operating station. The lower ends of rails 27 are connected by a tie bar 28 (Figs. 1 and 6) connecting the spaced rails 27 and being secured to a circular guide rail 29 properly supported in any usual manner and forming a continuation of the passageway for the can bodies passing through the operating stations. The can body "A" moves by gravity into a pocket 31 of a turret 32 secured to one end of a horizontal shaft 33 rotating in a bearing 34 formed in frame 24 and in a bearing 35 formed in the bracket 23 (Fig. 5).

The turret 32 is intermittently rotated in a step by step movement to carry the can bodies "A" from their received position through an idle station and thence through the first and second operating stations, after which the can body is discharged into a discharge chute 36 (Figs. 1, 3 and 6).

Movement is imparted to turret 32 by a Geneva mechanism comprising a Geneva wheel 37 secured to shaft 33 and having the usual radial slots 38 (Figs. 4 and 5).

A horizontal shaft 39 rotates in a bearing 41 formed in bracket 23 and in a bearing 42 carried by the frame 24. Shaft 39 carries a Geneva arm 43 upon which is rotatably mounted a Geneva roller 44 which operates during part of the rotation of shaft 39 and arm 43 within the radial slots 38 to impart a step by step movement to shaft 33. Shaft 39 also carries a spur gear 45 which meshes with a similar gear 46 carried on a horizontal cam shaft 47 journalled in bearings 48 formed in frame 25 and in bearings 49 formed in frame 24. Shaft 47 also carries a spiral gear 51 which meshes with a worm 52 secured to a horizontal drive shaft 53 rotating in bearings 54 formed in a bracket 55 mounted on bed 21 and in a bearing 56 formed in a brack-

et 57 secured to one side wall of bed 21 (see also Fig. 4). The drive shaft 53 receives power from any outside source, as by connection with a belt pulley 58 carried on one end of the shaft 53. Continual rotation of drive shaft 53 through the worm and gear connection described causes a corresponding rotation of the cam shaft 47, which rotation is communicated to shaft 39 to operate the Geneva arm 43 and to thereby impart intermittent movement to turret 32.

Chute 26 and the guide rails 27 are arranged intermediate the ends of the apparatus and mechanism arranged on one side of the chute 15 performs the operations upon the top end of the can body, and mechanism arranged on the opposite side performs the operations on the bottom end of the can body. In other words, mechanisms operating on the top end 20 of the can body are situated on the right hand side of the chute as disclosed in Figs. 3 and 5. In like manner, the mechanisms which operate upon the bottom end of the can are situated on the left hand side of Fig. 1 and on 25 the right hand side of Figs. 3 and 5.

The unflanged can body "A", as positioned by the turret at the first operating station, is brought to rest between the supporting shoulder mechanism and the can body flanging mechanism. The former mechanism operates upon the upper end of the can body and is illustrated in part in the left hand side of Fig. 11, and the flanging mechanism operates upon the bottom end of the can body, this mechanism being illustrated in Fig. 11 30 on the right hand side of the can body.

The shoulder-forming mechanism comprises an inner beading roller 61 mounted on a stud 62 eccentrically secured to the end of 40 a shaft 63 journaled in a sleeve 64 rotatable within a shell 65. A hollow cup member or outside beading roller 66 is threaded to the shell 65 and extends beyond the end of the same. These parts constitute a shoulder-forming head which is spaced from the positioned can end "A" when the latter is brought to rest by the turret 32. In the annular opening formed in the outer part of shell 66 there is disposed a ring 67 secured to the member 45 66 by means of screws 68 passing through a hardened steel washer 69 mounted adjacent to the roller 61. The ring 67 is formed with an inwardly extended annular ridge 71 adapted to cooperate during the shoulder-forming operation with an annular groove 72 formed in the roller 61.

The beading head is both rotatable and slidable, the sliding action positioning the head over the top end of the can body "A". Shell 65, carrying the hollow cup member 66, is rotatable about sleeve 64. Shaft 63 is moved bodily back and forth with the longitudinal movement of shell 65 and also has slight oscillation within sleeve 64. The mechanisms for rotating the beading head and

sliding the same into operating position will now be described.

Shell 65 has sliding and rotative movement within a bearing 73 carried on the frame 25 (Figs. 1, 5 and 7). Rotation is imparted to shell 65 and cup member 66 by a gear connection, comprising a gear 74 secured to the extremity of shell 65 and meshing with a gear 75 loosely mounted on a sleeve 76 keyed to shaft 47 and positioned between bearings 48 of the frame 25. Gear 75 in turn meshes with a gear 77 secured to a horizontal shaft 78 rotating in bearings 79 formed in frame 24 and in a bearing 81 formed in frame 25.

Shaft 78 carries a bevel gear 82 secured to one extremity thereof and meshing with a bevel gear 83 secured to the drive shaft 53 (see Fig. 1). Continual rotation of shaft 78 and gear 77 carried thereby imparts a similar rotation to the shell 65 and the hollow cup member 66.

The face of gear 75 is wider than the face of gear 74 and this permits the sliding movement of shell 65 without disengaging the gears 74 and 75.

Shaft 63, sleeve 64 and shell 65 are connected as a unit as regards their sliding action. Shaft 63 is formed with a spacer disc 84 where it connects with stud 62 and this construction prevents relative sliding 95 movement in one direction between the parts 63, 64 and 65. For example, shaft 63 cannot be moved toward the left (as viewed in Fig. 11) by reason of engagement with the disc 84 with the ends of the sleeve 64 and the shell 65. Relative sliding movement in the opposite direction between shell 65 and sleeve 64 is prevented by collar 85 pinned to the sleeve 64 beyond the extremity of shell 65 (Figs. 1 and 5). Relative sliding movement between 100 shaft 63 and sleeve 64 is prevented in a similar manner, as will be hereinafter set forth.

Sliding movement of the beading head is made by sliding sleeve 64 under cam action. In this sliding action, sleeve 64 slides within 110 a bearing 86 formed in frame 25, the opposite end of the sleeve being supported by the shell 65 in its bearing 73. Sleeve 64, intermediate collar 85 and bearing 86, carries a clamp block 87 formed on one end of a cross bar 88 which carries a cam following roller 89 operating in a cam groove 91 of a barrel cam 92 keyed to the sleeve 76 (see Figs. 5 and 7). Under the influence of cam 92, sleeve 64 is moved to position the hollow cup member 66 over the can body "A", collar 85 at such time striking against the end of the shell 65 and the inner end of sleeve 64 striking against the disc 84 of shaft 63. The parts of the beading head are thereby moved into operative position.

As illustrated in Fig. 11, as hollow cup member 66 is moved over the left hand end of can body "A", washer 69 engages the top edge 130 of the can body. Shell 65 and shaft 63 being

rotatable relative to each other, and roller 61 being eccentrically mounted upon shaft 63, which in turn is eccentrically mounted within sleeve 64, oscillation of shaft 63 changes the relative positions of roller 61 and cup member 66. During the movement of the beading head over the end of the can body, roller 61 is positioned concentrically with the hollow cup member 66, this being illustrated in Fig. 11. After the washer 69 has engaged the can body, shaft 63 is slightly oscillated, this action forcing the roller 61 toward the inner wall of the ring 67. Roller 61 thereupon engages the inner diameter of the can body "A" and the groove 72 thereof forces the material of the can body wall against the annular ridge 71 of the ring 67 and causes that part of the can body wall to conform to the shape of the ridge 71 and the groove 72. With the parts held in this position, the constantly rotating cup member 66 and the ring 67 carried thereby cause the ridge 71 to carry the entire circumference of the can body "A" in a circular path of travel. This action, by reason of the cooperation of the roller 61, which rotates about the stud 62, forms an inwardly pressed bead or supporting shoulder "B" into the upper wall of the can body "A". The resulting bead is illustrated at the left hand side of the can body "A", as illustrated in Fig. 13.

Shaft 63 is oscillated to engage the roller 61 against the can body "A" by the following mechanism: As illustrated in Figs. 1, 2 and 5, the outer extremity of shaft 63 carries a pinion 93 which meshes with a gear segment 94 oscillating about a stud 95 carried in a bearing 96 formed in frame 25. The segment 94 is formed with an extension arm 97 to which is pivotally connected an adjustable connecting link 98 in turn pivoted to an arm of a bell crank lever 99. Bell crank lever 99 is pivoted about a fixed stud 101 carried by a boss 102 formed in frame 25. An arm 103 of bell crank lever 99 carries a cam following roller 104 which operates within the groove of a face cam 105 secured to the shaft 47.

Oscillation of shaft 63 is thus cam controlled to move the roller 61 relative to ring 67 carried by the hollow cup member 66. The pinion 93, being secured to the shaft 63 beyond the end of sleeve 64, confines the latter between the disc part 84 of shaft 63 and the pinion 93. Sliding of sleeve 64 by the mechanism just described in either direction, therefore, causes a corresponding movement of the shaft 63.

The flanging mechanism comprises an inner flanging roller 106 mounted on a stud 107 eccentrically secured to the end of a shaft 108 journaled in a sleeve 109 rotatable within a shell 111. A hollow cup member, operating as an integral flanging roller 112, is threaded to the shell 111 and extends beyond the end 65 of the same. These parts constitute the

flanging head which is spaced from the positioned can body "A" when the latter is brought to rest by the turret 32. In the annular opening formed in the outer part of shell 112, there is disposed a ring 113 secured to the member 112 by means of screws 114 passing through a hardened steel washer 115 mounted adjacent to the roller 106. The ring 113 is formed with an annular groove 116 adapted to cooperate during the flanging operation with an annular ridge 117 formed on the roller 106.

The flanging roller 106 is associated with a can body gripping device (illustrated on the right hand side of Fig. 11). Stud 107 of shaft 108 carries a bushing 118 within the flanging roller 106. Stud 107 is connected with shaft 108 by means of a spacer disc 119 positioned on the inside of and spaced from the washer 115. Stud 107 is also provided with an enlarged head 121 which retains the bushing in rotative position. A retaining cap 122 is positioned over the bushing 118 and is secured to the flanging roller 106 by screws 123, which pass through a rubber disc washer 124 confined within a knock-off ring 125 slidingly held between cap 122 and flanging roller 106. In the normal position of the parts just described, which position is illustrated in Fig. 11, the knock-off ring 125 is held concentric with cap 122 and flanging roller 106 by means of the rubber washer 124, the outer peripheral edge of the knock-off ring 125 extending beyond the peripheral edge of the flanging roller 106. The parts are in this position when the flanging head is inserted over the bottom end of can body "A". The various steps in the operation of these parts during the flanging operation and immediately following will be described hereinafter.

The flanging head is both rotatable and slidable, the sliding action positioning the head over the bottom end of the can body at the same time that the beading head is positioned over the top end. Shell 111 carrying the hollow cup member 112 is rotatable about sleeve 109. Shaft 108 is moved bodily back and forth with the longitudinal movement of shell 111 and also has slight oscillation within sleeve 109. These devices and the movements imparted to the various parts thereof are similar in every way to the devices and movements of the shoulder forming mechanism. The devices for rotating the flanging head and sliding it into operating position will now be described.

Shell 111 has sliding and rotating movement within a bearing 120 formed in frame 24 (Figs. 1 and 5). Rotation is imparted to shell 111 and cup member 112 by a gear connection comprising a gear 126 secured to the extremity of shell 111 and meshing with a gear 127 loosely mounted on a sleeve 128 keyed to shaft 47 and positioned between bearings 49 of frame 24. Gear 127 in turn

meshes with a gear 129 secured to the horizontal shaft 78.

The face of gear 127 is wider than the face of gear 126 and this permits the sliding movement of shell 111 without disengaging the gears 126 and 127. Shaft 108, sleeve 109 and shell 111, as far as their sliding action is concerned, are connected as a unit. Shaft 108, by means of spacer disc 119, prevents sliding movement in one direction between the parts 108, 109 and 111. For example, shaft 108 cannot be moved toward the right (as viewed in Fig. 11) by reason of the engagement of the disc 119 against the ends of the sleeve

15 109 and the shell 111. Relative sliding movement in the opposite direction between the shell 111 and sleeve 109 is prevented by a collar 131 pinned to the sleeve 109 beyond the extremity of the shell 111 (Figs. 1 and 5). 20 Relative sliding movement between shaft 108 and sleeve 109 is prevented in a similar manner, as will be hereinafter set forth.

Sliding movement of the flanging head is made by sliding sleeve 109 under cam action. 25 In this movement, sleeve 109 slides within a bearing 132 formed in frame 24, the opposite end of the sleeve being supported by the shell 111 in its bearing 120. Sleeve 109, intermediate collar 131 and bearing 132, carries a 30 clamp block 133 (Figs. 5 and 9). Block 133 carries a cam following roller 134 operating in a cam groove 135 formed in a double barrel cam 136 keyed to sleeve 128 and therefore rotating with shaft 47. Clamp block 35 133 slides along a rock shaft 137 journalled in bearings 138 formed in frame 24. By means of this sliding connection of clamp block 133 with shaft 137, the former is prevented from rotating relative to the center of 40 sleeve 109 and this insures a proper holding of the cam following roller 134 within the cam groove 135.

Under the described connection, therefore, 45 cam 136 controls the sliding movement of the flanging head and positions it over the bottom end of can body "A" at the proper time. Sliding movement of sleeve 109 causes collar 131 carried thereby to strike against the end of the shell 111 and thus move 50 the flanging head bodily into the described position.

As illustrated in Fig. 11, as hollow cup member 112 is brought to its inner position (this being the position illustrated), the same 55 is positioned over the right hand or bottom end of the can body "A", washer 115 at such time engaging the end of the body. During this positioning of the flanging head over the can body, cup member 112 is concentric with 60 the other described parts of the head and this permits the flanging roller 106 and its associated parts to move into the interior of the can body "A". After the washer 115 has engaged the can body, shaft 108 is slightly oscillated, this action forcing the ring 125 first

into contact with the can body wall and then moving the flanging roller 106 toward the inner wall of the ring 113. After engagement of the knock-off ring 125 with the can body wall, the rubber washer 124 yields and permits radial sliding movement between the ring and the flanging roller 106. Roller 106 forces the end of the can body wall outwardly by engagement with its annular ridge 117, this action moving the material of the can body wall against the annular groove 116 of the ring 113. This causes that part of the can body wall to conform to the shape of the ridge 117 and groove 116.

With the parts held in this position, the 70 constantly rotating cup member 112 and the ring 113 carried thereby cause the groove 116 to carry the entire circumference of the can body "A" in a circular path of travel. This action, by reason of the cooperation of the flanging roller 106 rotating at this time with the bushing 118 about the stud 107, forms an 75 outwardly pressed flange "C" on the lower end of the can body "A". The resulting flange is illustrated at the right hand side of 80 the can body "A" in Fig. 12. Shaft 108 is oscillated to move the flange roller 106 and the parts carried thereby to the flanging position, just described, by mechanism which 85 will now be described.

As illustrated in Figs. 1, 5 and 10, the outer 90 extremity of shaft 108 carries a pinion 139 which meshes with a gear segment 141 carried on one extremity of rock shaft 137. Shaft 137, intermediate rear bearing 138 and 95 block 133, has secured thereto an arm 142 connected by means of an adjustable link 143 with one arm of a bell crank lever 144 (see also Fig. 9). Bell crank lever 144 is pivoted about a shaft 145 carried by a bracket 146 formed in frame 24. Another arm 147 of bell 100 crank lever 144 carries a cam following roller 148 which operates within the groove of a face cam 149 keyed to the sleeve 128 and therefore rotating with the shaft 47.

Oscillation of shaft 108 is thus cam controlled to move the flanging roller 106 and parts 122 and 125 relative to the can body to 105 perform the flanging operation just described. Opposite movement of shaft 108 withdraws the flanging roller 106 from flanging position, whereupon the yielding washer 124 restores the knock-off ring 125 to central position, this action stripping the can body "A" from the flanging groove 116 and positioning the can centrally of the stud 107, this being the normal position. Pinion 139 being secured to shaft 108 just beyond the end of sleeve 109 confines the latter between the disc part 119 of shaft 108 and the said pinion 139. Sliding of sleeve 109 in either direction, 110 therefore, causes a corresponding movement of shaft 108.

As illustrated in Fig. 11, the shoulder forming or beading head is provided with de- 115

vices for holding the flanged and beaded can body "A" in central longitudinal position as the shoulder forming and flanging heads are separated after operation at the first station. 5 This mechanism is disclosed at the left hand side of Fig. 11 and comprises stripper pins 151 resting within slots 152 formed in the cup shaped member 66. The pins 151 are riveted to a ring 153 having an annular tongue and 10 groove connection 154 with a split ring 155, the halves of which are clamped together by bolts 156. The split ring 155 is secured to bearing 73 at the point 157 (Fig. 5). By means of this connection, split ring 155 is 15 held in a fixed position at all times, and ring 154 to which pins 151 are secured rotates within the split ring 155 in unison with the rotation of the cup shaped member 66.

After the shoulder forming operation has 20 been completed and the beading head is moved backwardly, member 66 moves over the ends of the stripper pins 151, these pins passing entirely through the slots 152 and also through slots 158 formed in the washer 25 69. The upper end of can body "A", which has a tendency to be carried backwardly with the beading head, strikes against the forward ends of pins 151 and is prevented from further movement while the beading head is further withdrawn from the said can body. At 30 the same time, the flanging head has been withdrawn from the opposite end of the can body. The can body is then in position to be moved by the turret 32 to the second operating 35 station.

The flanged and beaded can body "A" 40 when positioned at the second operating station is brought into axial alignment with the drum head inserting and securing mechanism. Previous to the positioning of the can body at this station, a drum head or disc "D" has been brought into the inserting and securing head by mechanism which will first be described. Drum head "D" is brought into the 45 machine upon a horizontal chain conveyor 161 (Figs. 1, 2 and 3). The conveyor chain operates within a groove 162 formed in a channel member 163 secured to bracket 164 mounted upon frame 25. Chain 161 operates 50 over a sprocket 165 mounted on a shaft 166 carried in the bracket 164. This chain may be a part of an independent machine and is driven in any usual or preferred manner. A series of spaced flights 167, carried by the 55 links of the chain 161, insure proper travel of the disc "D" within the channel 163, and as each disc is moved over the sprocket 165 it is projected into a hopper 168 carried by the drum head inserting and securing mechanism.

As disc "D" falls from the conveyor chain 60 161, it strikes against a deflecting plate 169 positioned on the interior of hopper 168 (see Figs. 12, 13 and 14). Plate 169 causes disc 65 "D" to assume a substantially vertical posi-

tion, and as it falls within the hopper 168 it comes to rest upon the forward projection 171 of a feed finger 172 pivoted at 173 on a block 174 secured to the rear wall of hopper 168. The drum head inserting and securing mechanism comprises a non-rotatable head member 175 secured to the forward end of a sliding shaft 176. Hopper 168 is mounted upon the head 175 and is secured thereto at 177 (Fig. 3).

As head 175 is moved backwardly with the sliding of shaft 176 by mechanism which will be hereinafter described, the upper end of the feed finger 172 strikes against an adjustable screw 178 held in adjusted position by means of a lock nut 179 upon the bracket 164. A coil spring 181, positioned between the upper end of finger 172 and the block 174, yields at such a time and permits pivoting 80 of the finger 172 about its pivot 173, this action withdrawing the lower extension 171 from within the hopper 168. Disc "D" thereupon falls through a slot 182 into a chamber or pocket 183 formed in the head 175. In this position, disc "D" rests within holding 85 fingers 184 pivoted at 185 to head 175, this position being shown in Fig. 13.

There are three holding fingers 184, one resting directly beneath the disc "D" and two being positioned on opposite sides and central of the said disc. The upper edge of the disc "D" is prevented from forward displacement by a projection 186 formed on the forward end of a lever 187 pivoted at 188 to the hopper 168 (Fig. 14). The end of lever 187 90 opposite the projection 186 carries a cam following roller 189 held in upward position by a spring 191 secured at 192 to the hopper 168, the roller 189 resting against the under surface of a cam bar 193 adjustably secured as at 95 194 to the bracket 164 as illustrated in Fig. 3. While head 175 is in its rear position, this being the position of the head when it receives the disc "D", the projection 186 is held in 100 front of the upper part of the disc.

From its rearmost position, head 175 is 105 moved toward the positioned can body "A" resting on the guide rail 29 and held within the turret 32. This movement of head 175 is accomplished by a sliding of shaft 176 within bearings 195 carried by the frame 25 (Figs. 3, 7 and 13). Shaft 176 is held by a clamp block 196 formed on the crosshead 88 opposite block 87 and moves in unison with the crosshead 110 under the action of cam 92 previously described.

Head 175 carries a number of curling rollers 197 loosely mounted on studs 198 radially disposed about the center of the head 175, each roller 197 being positioned within a pocket 199 cut in the head 175 (Figs. 13 and 14). As head 175 moves toward the right (as viewed in Fig. 13) the forward face of the same adjoining the pocket 183 and the forward edges 115 of rollers 197 engage the rear face of the 120

positioned disc "D". The disc thereupon is moved toward the positioned can body "A". As head 175 moves the hopper 168 and the parts carried thereby toward the end of the cam bar 193, roller 189 engages the forward end of the bar and moves upon a cam extremity 201. This causes a lowering of the roller 189 and a corresponding pivoting of the lever 187 against the action of the spring 191. The projection 186 of the bar 187 is therefore lifted to clear disc "D" being moved forward with the moving head 175.

During this forward movement of head 175, the holding fingers 184 are moved about their pivots 185 to release disc "D" just prior to its passing into the open upper end of the can body "A". Each finger 184 (Figs. 12 and 13) is provided with a cam extremity 202 which is engaged during the forward movement of head 175 by a fixed finger 203 adjustably held by a screw 204 on a disc 205 secured by a screw 206 to the forward bearing 195. Finger 184 is moved about its pivot 185 or is held in any of its positions by the fixed finger 203. The position assumed depends upon the location of the engaging finger 203 relative to the pivot 185. For example, when finger 203 engages extremity 202 of finger 184, this being back of its pivot, the forward ends of finger 184 will be held outwardly, but when finger 203 engages finger 184 forward of its pivot, the forward end of the latter finger will be held inwardly. Fig. 12 illustrates this first position and Fig. 13, the second position.

When a finger 184 is in the position shown in Fig. 12, a forward hook 207 thereof is moved free of disc "D" and also free of the can body "A". Continued forward movement of head 175 thereupon inserts disc "D" within the upper end of the can body "A" and brings the outer edge of the can body against the curling rollers 197. The can body "A" at such time is rotating about its own axis by cooperation with a rotating head now to be described.

In axial alignment with head 175 and positioned at the opposite end of the can body "A" at the second station is a rotating backing head 208 carried on the forward extremity of a rotating shaft 209. Head 208 (as illustrated in Fig. 13) is clear of the can body "A" as it is brought into position at the second station. Backing head 208 normally rotates with the shaft 209 and as shaft 209 and head 208 are moved toward the can body in unison with the forward movement of head 175, a boss 211 carried on the face of the backing head 208 moves within the bottom end of the positioned can body at the same time that disc "D" is moved into the top end of the same. As head 208 engages tightly within the can body "A", the latter starts rotating with the rotation of the head 208 and the shaft 209. The head 208 is

loosely mounted on a stud 212 formed in the end of shaft 209 and slips upon the stud until the can body gains sufficient momentum to rotate in unison with the shaft 209. This permits an easier action of the parts without damage to the can body "A".

The mechanism for rotating the shaft 209, will now be described. Shaft 209 both rotates and slides within bearings 213 formed on the upper end of frame 24 (Figs. 3, 8, 9 and 10) and carries a pinion 214. Pinion 214 meshes with the gear 127, this connection rotating shaft 209 in unison with shell 111 of the flanging head. The face of gear 214 is less than the face of gear 127, and this permits relative sliding movement of the gears without bringing their teeth out of mesh.

Shaft 209 is slid back and forth within its bearings by means of a cam-controlled device comprising a clamping block 215 loosely mounted on shaft 209 and positioned between collars 216. Block 215 carries a cam following roller 217 operating within a groove 218 formed in the double barrel cam 136. The block 215 is held against rotation about the shaft 209 by a sliding connection with a fixed rod 219 held within bearings 221 formed in frame 24. This construction permits a sliding of the block 215 along the rod 219 but insures a proper operating position of the cam roller 217 within its cam groove 218. Shaft 209 and head 208 are thus rotated and at the same time moved into engagement with the can end "A" for the drum head inserting operation.

The can body "A" carried with the rotating head 208 turns within the fixed head 175 and the upper edge thereof being pressed to engagement with the rollers 197 rotates them upon their axes. Inasmuch as the pressure of the heads 175 and 208 on the can body edges continues after the can body "A" has engaged the rollers 197, the upper edge thereof is bent inwardly by grooves formed in the rollers, the bending edge forcing against the disc "B" and moving around into the curl "E" (as illustrated in Fig. 12). This moving of the disc "B" inwardly with the curling of the upper end of the can body "A" forces the disc against the shoulder "B" and locks the same between the shoulder "B" and the curl "E".

The drumhead inserting and securing mechanism and the rotating backing head and its associated members are thereupon withdrawn from the can body "A" and move back into normal position. The turret 32 is thereupon given a part rotation and the flanged and headed can body "A" is rolled over the end of the rail 29 and into the discharge chute 36 where it falls by gravity from the machine.

It is thought that the invention and many of its attendant advantages will be under-

stood from the foregoing description, and it will be apparent that various changes may be made in the form, construction and arrangement of the parts without departing from the 5 spirit and scope of the invention or sacrificing all of its material advantages, the form hereinbefore described being merely a preferred embodiment thereof.

I claim:

- 10 1. In an apparatus for preparing drum head can bodies, the combination of a movable can body carrier, means for forming a supporting shoulder in one end of the can body, feeding devices for positioning a drum head in alignment with the shouldered end of the can body, and means for inserting the positioned drum head within the can body and adjacent the shoulder.
- 15 2. In an apparatus for preparing drum head can bodies, the combination of a movable can body carrier, means for forming a supporting shoulder in one end of the can body, feeding devices for positioning a drum head in alignment with the shouldered end of the can body, means for inserting the positioned drum head within the can body and adjacent the shoulder, and mechanism for securing the drum head against the can body shoulder.
- 20 3. In an apparatus for preparing drum head can bodies, the combination of a movable can body carrier, means for forming a supporting shoulder in one end of the can body, feeding devices for positioning a drum head in alignment with the shouldered end of the can body, means for inserting the positioned drum head within the can body and adjacent the shoulder, and mechanism for securing the drum head against the can body shoulder.
- 25 4. In an apparatus for preparing drum head can bodies, the combination of a movable can body carrier, means for forming a supporting shoulder in one end of the can body, feeding devices for positioning a drum head in alignment with the shouldered end of the can body, means for inserting the positioned drum head within the can body and adjacent the shoulder, the said can body carrier presenting the can body to the shoulder forming, drum head inserting and drum head securing mechanisms, and holding the same in proper position during the operations of those mechanisms.
- 30 5. In an apparatus for preparing drum head can bodies, the combination of a movable can body carrier, means for forming a supporting shoulder in one end of the can body, means for forming a flange in the opposite end of the can body, feeding devices for positioning a drum head in alignment with the shouldered end of the can body, and means for inserting the positioned drum head within the can body and adjacent the shoulder.
- 35 6. In an apparatus for preparing drum head can bodies, the combination of a movable can body carrier, means for forming a supporting shoulder in one end of the can body, feeding devices for positioning a drum head in alignment with the shouldered end of the can body, means for inserting the positioned drum head within the can body and adjacent the shoulder, mechanism for secur-

ing the drum head against the can body shoulder, and actuating devices for moving the can body carrier, the shoulder forming, drum head inserting and drum head securing mechanisms in proper time relation.

6. In an apparatus for preparing drum 70 head can bodies, the combination of a movable can body carrier comprising a pocketed turret, a feed-in chute for positioning a can body into a pocket of the turret, means for forming a supporting shoulder in one end of 75 the can body, feeding devices for positioning a drum head in alignment with the shouldered end of the can body, and means for inserting the positioned drum head within the can body and adjacent the shoulder.

7. In an apparatus for preparing drum head can bodies, the combination of a movable can body carrier, means for forming a supporting shoulder in one end of the can body, 85 said means comprising internal and external beading rollers, feeding devices for positioning a drum head in alignment with the shouldered end of the can body, and means for inserting the positioned drum head within the can body and adjacent the shoulder.

8. In an apparatus for preparing drum head can bodies, the combination of a movable can body carrier, means for forming a supporting shoulder in one end of the can body, feeding devices for positioning a drum head in alignment with the shouldered end of the can body, means for inserting the positioned drum head within the can body and adjacent the shoulder, and a holding finger for retaining the drum head in aligned position for said insertion.

9. In an apparatus for preparing drum head can bodies, the combination of a movable can body carrier, means for forming a supporting shoulder in one end of the can body, feeding devices for positioning a drum head in alignment with the shouldered end of the can body, means for inserting the positioned drum head within the can body and adjacent the shoulder, said inserting means comprising a reciprocating head carrying holding fingers pivotally mounted thereon, said fingers retaining the drum head in aligned position for its insertion, and actuating devices for pivoting the holding fingers and releasing the drum head as said drum head enters within the end of the can body.

10. An apparatus for preparing drum head can bodies, comprising in combination a movable can body carrier, a passageway along which can bodies are conveyed by the carrier, operating stations arranged along the path of travel of the can body and at which can bodies are brought to rest by the said carrier, mechanisms positioned at one station for forming a supporting shoulder in one end of the can body and for forming a flange in the opposite end of the can body as it is held at rest at the station, mechanisms positioned at 125 130

a second station for inserting and securing a drum head within the can body adjacent the said shoulder as it is held at rest at the second station, and feeding devices for delivering a drum head to the second station.

11. In an apparatus for preparing drum head can bodies, the combination of a movable can body carrier, means for forming a supporting shoulder in one end of the can body, means for forming a flange in the opposite end of the can body, said flanging means comprising internal and external flanging rollers, feeding devices for positioning a drum head in alignment with the shouldered end of the can body, and means for inserting the positioned drum head within the can body and adjacent the shoulder.

12. In an apparatus for preparing drum head can bodies, the combination of a movable can body carrier, means for forming a supporting shoulder in one end of the can body, feeding devices for positioning a drum head in alignment with the shouldered end of the can body, means for inserting the positioned drum head within the can body and adjacent the shoulder, said inserting means comprising a reciprocating head, and mechanism for securing the drum head within the can body, said mechanism comprising curling rollers carried by the reciprocating head, said rollers bending the edge of the can body into an annular curl, thereby clamping said drum head between the curl and the shoulder of the can body.

13. In an apparatus for preparing drum head can bodies, the combination of a movable can body carrier for receiving a can body from a feed-in chute and transferring it to a station, a drum head feeding device adapted to receive a drum head and positioning it at said station in axial alignment with and adjacent to one end of the can body, and inserting means at said station for inserting the drum head into the end of the positioned can body against an internal shoulder of said body.

14. In an apparatus for preparing drum head can bodies, the combination of a movable can body carrier for receiving a can body from a feed-in chute and transferring it to a station, a drum head feeding device adapted to receive a drum head and positioning it at said station in axial alignment with and adjacent to one end of the can body, inserting means at said station for inserting the drum head into the end of the positioned can body, and securing mechanism at said station for curling inward an edge of the can body and securing the drum head within the same while it is positioned at said station.

15. In an apparatus for preparing drum head can bodies, the combination of a movable can body carrier for receiving a can body and transferring it to a station, a beading mechanism at said station for forming a

drum head supporting internal shoulder in one end of the can body, said shoulder being smaller than said end of the body, and a flanging mechanism at said station for flanging the opposite end of the can body.
